DESIGN FOR A BULLETIN BOARD

Fred H. Eisenhut, Racine, Wis., assignor to Belle City Malleable Iron Company, Racine, Wis., a corporation of Wisconsin

Application November 8, 1938, Serial No. 80,967

Term of patent 14 years

To all whom it may concern:

Be it known that I, Fred H. Eisenhut, a citizen of the United States, residing at Racine, in the county of Racine and State of Wisconsin, have invented a new, original, and ornamental Design for a Bulletin Board, of which the following is a specification, reference being had to the accompanying drawing, forming part thereof.

In the drawing,

Figure 1 is a top plan view of the bulletin board showing my design;

Figure 2 is a front view of the bulletin board of my design; and,

Figure 3 is a side view thereof, both sides being the same.

I claim:

The ornamental design for a bulletin board, as shown and described.

FRED H. EISENHUT.
